UNITED STATES PATENT OFFICE.

OSCAR GRIMWOOD, OF OWENSVILLE, INDIANA.

STREET-SWEEPER.

949,069.

Specification of Letters Patent. Patented Feb. 15, 1910.

Application filed March 23, 1909. Serial No. 485,349.

To all whom it may concern:

Be it known that I, OSCAR GRIMWOOD, a citizen of the United States, residing at Owensville, in the county of Gibson and 5 State of Indiana, have invented a new and useful Street-Sweeper; and I do hereby declare the following to be a full, clear, and exact description of the invention, such as will enable others skilled in the art to which 10 it appertains to make and use the same.

This invention pertains to a new and useful street sweeper, and it has for its object to provide a novel and efficient device of this character, by which the sweepings of a 15 street are automatically elevated through pneumatic means and afterward delivered into a suitable receptacle carried by the apparatus.

A further object is to provide an inexpensive structure of this design, in which the rotary brush, as well as the suction pipe, may be raised or lowered, for obvious purposes.

A further object of the invention is the 25 provision of means for holding the brush yieldably in contact with the street when being swept, and the pneumatic suction pipe for elevating the sweepings is provided with means of a resilient character, so as to allow 30 the same to easily and readily pass any obstruction that may be in the path thereof.

The invention comprises further objects and combinations of elements which will be hereinafter fully described, shown in the accompanying drawings, and the novel features thereof will be pointed out by the appended claims.

To obtain a full and correct understanding of the details of construction, combinations of features, elements and advantages, 40 reference is to be had to the hereinafter set forth description and to the accompanying drawings in connection therewith, wherein—

Figure 1 is a top plan view of the street 45 sweeper, showing the novel construction thereof and the electric motors carried by the frame of the apparatus. Fig. 2 is a side elevation, clearly showing the operative parts in position and in readiness to perform the 50 functions for which they are provided. Fig. 3 is a longitudinal sectional view through the apparatus, clearly illustrating the interior structure thereof.

In regard to the accompanying drawings, 55 wherein similar reference characters indicate corresponding parts in the several views, 1

designates the supporting frame for the operating parts of the apparatus. This supporting frame is provided with the usual traction wheels 2, that is, the rear traction 60 wheels and the usual front steering wheels 3, which may be steered in the usual way, that is, by beveled gear connections 4, with an angularly disposed shaft or rod 5, on which the usual hand wheel 6 may be provided, and positioned in close proximity to the operator of the apparatus.

The axle 7 of the rear traction wheels is provided with a pair of sprocket wheels 8, which are positioned adjacent the ends of 70 the axle. Mounted in suitable bearings of the frame of the apparatus is a shaft 9, on which at the ends thereof, are sprockets 10, about which and the sprockets 8, chains 11 travel. Also carried by the shaft 9 is a beveled gear 12; and positioned forward of the frame of the apparatus are two electric motors 13 and 14. The motor 14 has an extended shaft 15, the end of which is supported in suitable bearing, as shown at 16, 75 and the extremity of the said shaft 15 is provided with a beveled gear 17, which meshes with the beveled gear 12, as shown clearly in the top plan view of the drawing.

Mounted in suitable bearings 18 of the 80 frame of the apparatus is an additional countershaft 19, on which is mounted a beveled gear 20 and a pulley 21, about which pulley a suitable belt 22 travels. This belt 90 also travels about the pulley 23 of the pneumatic suction fan 24, which is suitably supported upon the frame of the apparatus.

The motor 13 is provided with an extended shaft 25, the end of which is mounted in a suitable supporting bearing 26, and upon 95 the extremity of said shaft 25 is a beveled gear 27, which is designed to mesh with the beveled gear 20, mounted upon the counter-shaft 19.

The extended shafts 15 and 25 of the electric motors 13 and 14 are provided with suitable clutch mechanisms 28 and 29, which are provided with suitable operating handles 30 and ratchet engaging pawls 31, of the usual type. These handles are positioned in 10 close proximity to the operator, so that he may easily and quickly throw the clutch mechanism in and out of gear, as will be clearly evident from the annexed drawings.

Extending laterally and curved rearwardly and downwardly, then forwardly is 110 the pneumatic suction pipe 32, which is

flared, as at 33, to equal the width of the frame of the apparatus. The forward end of the pneumatic suction pipe is disposed beneath and slightly rearward of the rotating brush 34, which is mounted in suitable bearings 35 of the pivotally mounted arms 36, the shaft 37 of this rotating brush is provided upon one of its ends with a sprocket wheel 38, about which a sprocket chain 39 travels. This sprocket chain 39 also travels about a sprocket wheel 40, which is carried by and rotatable with the countershaft 19. The countershaft, receiving motion transmitted from the electric motor 13, operates the pulley 21 which in turn operates the pneumatic suction fan 24 and the rotary brush 34, through the medium of the sprocket wheels 38 and 40 and the sprocket chain 39.

The pivotally mounted arms 36 have rods 42 connected thereto, the upper ends of which are connected to the bell crank levers 43, that is to say, after passing through the frame of the apparatus, as clearly shown. This bell crank lever 43 is fulcrumed in a bracket or standard 44 of the frame and one of its arms 45 is pivotally connected to a pitman rod 46. This pitman rod 46 is connected to a lever 47 which is fulcrumed, as at 48, to the frame of the apparatus. This lever 47 is provided with a pawl 49, which is designed to engage teeth 50 of the quadrant 51. This quadrant 51 is secured to and carried by the frame of the apparatus. Pivotally connected to the pawl 49 is a rod 52, which is connected to a hand grip 53. This hand grip 53 is located adjacent the handle 54 of the said lever, as clearly shown. Surrounding the rod 52 and positioned between a bracket thereof and a shoulder 55 of the lever is a coiled spring 56, the tendency of which is to hold the pawl in engagement with the teeth of the said quadrant, as will be clearly evident. When the lever 47 is moved forward of the frame of the apparatus, the coiled spring 57 is under tension, as will be understood. This spring 57 surrounds the rod 42, and is designed for the purpose of holding the pivotally mounted frame of the rotary brush downward toward the street, as is evident from the drawing.

The pivotally mounted arms 36 are provided with lugs 58, through apertures 59 of which the rods 60 extend. These rods 60 are pivotally connected to the pneumatic suction pipe, as shown clearly at 61, and the extremities of the rods which extends through the apertures of said lugs are provided with nuts or adjusting members 62, between which and the lugs 58 coiled springs 63 are disposed, in order to provide yielding braces for the pneumatic suction pipe, as shown clearly in the drawings.

Upon the sides of the flared portion of the pneumatic suction pipe are pivotally mount-

ed two bearing rollers 65, which are designed to contact with the street or pavement, so as to hold the flared portion of the pneumatic suction pipe slightly above the street or pavement, as will be clearly understood.

Extending angularly and upwardly from the pneumatic suction fan casing 66 is a delivering pipe 67, which communicates with a dust collector or hopper 68, the contents 75 of which are emptied into a receptacle 69. The receptacle and the dust collector or hopper 68 are supported and carried by the rear portion of the frame of the apparatus, there being a door 70 to allow of access into 80 the receptacle, and which may be raised for the purpose of emptying the receptacle after being filled.

The forward portion of the frame of the apparatus is provided with a suitable seat 85 71 for the operator and a foot-rest 72, as clearly shown.

It is plainly manifest that as the apparatus is driven through the streets or over the pavement, the dirt and the refuse of the 90 street are readily swept, and afterward quickly elevated through the means of the pneumatic suction fan and pipe, into the receptacle 69.

From the foregoing, the essential features, 95 elements and the operation of the device, together with the simplicity thereof, will be clearly apparent.

Having thus fully described the invention, what is claimed as new and useful is:— 100

1. In a street sweeper, a framework, a pneumatic suction fan carried thereby, a rotary brush, pivotally mounted arms for supporting the brush, said pneumatic suction fan having a pneumatic suction pipe with 105 its end disposed beneath and slightly in the rear of the said brush, connections between the suction pipe and the pivotally mounted arms in order to allow the suction pipe to have a yielding action, and means for raising and lowering the said pivotally mounted frame.

2. In a street sweeper, a framework, a pneumatic suction fan carried thereby, a rotary brush, pivotally mounted arms for supporting the brush, said pneumatic suction fan having a pneumatic suction pipe with 115 its end disposed beneath and slightly in the rear of the said brush, connections between the suction pipe and the pivotally mounted 120 arms in order to allow the pipe to have a yielding action, and means for operating the pneumatic suction fan.

3. In a street sweeper, a framework, a pneumatic suction fan carried thereby, a rotary brush, pivotally mounted arms for supporting the brush, said pneumatic suction fan having a pneumatic suction pipe with 125 its end disposed beneath and slightly in the rear of the said brush, connections between 130

the suction pipe and the pivotally mounted arms in order to allow the pipe to have a yielding action, means for yieldingly holding the pivotally mounted frame downward, and 5 means for operating the pneumatic suction fan.

4. In a street sweeper, a framework, a pneumatic suction fan carried thereby, a rotary brush, pivotally mounted arms for supporting the brush, said pneumatic suction fan having a pneumatic suction pipe with its end disposed beneath and slightly in the rear of the said brush, connections between the suction pipe and the pivotally mounted arms in order to allow the pipe to have a yielding action, means for yieldingly holding the pivotally mounted frame downward, 10 means for raising and lowering the pivotally mounted arms and the rotary brush, and 15 means for operating the pneumatic suction fan.

5. In a street sweeper, a framework, a pneumatic suction fan carried thereby having a pneumatic suction pipe extended laterally therefrom, curved rearwardly and downwardly and then forwardly, said framework having pivotally mounted arms, a rotary brush journaled in said arms, means for simultaneously operating the pneumatic 25 fan and the said brush, means for yieldingly holding the pivotally mounted frame downward, connections between the suction 30

pipe and the pivotally mounted arms in order to allow the pipe to have a yielding action, means for raising and lowering the 35 pivotally mounted arms, driving mechanism for the apparatus, a receptacle for receiving the sweepings of the street, and anti-frictional rollers carried by the pneumatic suction pipe.

6. In a street sweeper, a framework, a pneumatic suction fan carried thereby having a pneumatic suction pipe extended laterally therefrom, curved rearwardly and downwardly and then forwardly, said 40 framework having pivotally mounted arms, a rotary brush journaled in said arms, means for simultaneously operating the pneumatic fan and the said brush, means for yieldingly holding the said arms downward, means for raising and lowering the pivotally mounted arms, driving mechanism for the apparatus, a receptacle for receiving the sweepings of the street, and anti-frictional rollers carried by the pneumatic 45 suction pipe.

In testimony whereof I have signed my name to this specification in the presence of two subscribing witnesses.

OSCAR GRIMWOOD.
